Malcolm S. Park, Mount Kisco, N. Y., assignor to The Singer Manufacturing Company, Elizabeth, N. J., a corporation of New Jersey

Application March 11, 1954, Serial No. 29,476

Term of patent 14 years

(Cl. D70—1)

To all whom it may concern:

Be it known that I, Malcolm S. Park, a citizen of the United States, residing at Mount Kisco, in the county of Westchester and State of New York, have invented a new, original, and ornamental Design for a Sewing Machine, of which the following is a specification, reference being had to the accompanying drawings, forming a part thereof.

Fig. 1 is a front elevational view of a sewing machine embodying the design in accordance with the present invention.

Fig. 2 is a rear elevational view of the sewing machine shown in Fig. 1.

Fig. 3 is a top plan view of the sewing machine shown in Fig. 1.

Figs. 4 and 5 are head end and standard end views, respectively, of the sewing machine shown in Fig. 1.

I claim:

The ornamental design for a sewing machine, substantially as shown.
